BLOOD TRANSFER MECHANISM

Peter F. Salisbury, Beverly Hills, Calif.

Application May 10, 1949, Serial No. 92,310

11 Claims. (Cl. 128—214)

1

This invention relates to that branch of the medical art in which all or a large part of the blood supplies of two persons are interchanged, and has as a general object to provide an apparatus for effecting and for metering the interchange of blood between a patient and a donor. The invention is directed to the general type of apparatus disclosed in my earlier application Serial No. 70,013, filed January 10, 1949, of which the present application is in part a continuation. A particular object is to provide for equalizing the flow in both directions.

Another object is to provide a blood metering apparatus of a high degree of accuracy.

Another object is to provide a blood interchange and/or metering apparatus including means for automatically metering the blood being interchanged and for automatically shifting from one cycle of operation to another under the control of a metering mechanism.

A further object is to provide a novel blood interchange and/or metering apparatus including novel control mechanism, sensitive to the rise and fall of blood level in a metering chamber, for automatically controlling a cycling action in the apparatus.

A further object of the invention is to provide a blood interchange and/or metering apparatus having electric motor driven means for automatically reversing the cycle of operation thereof in response to the rise and fall of blood level in a metering chamber.

Another object is to provide a blood interchange and/or metering apparatus having electric motor driven means for pumping blood from a patient or donor into a metering chamber, with means responsive automatically to upper and lower liquid level limits in said chamber, for recurrently arresting the pumping action, reversing the movement of the blood and evacuating the chamber, and then again reversing the movement and starting the pumping action anew for another cycle of operation.

Another object is to provide such an apparatus in which the subjection of the blood to pumping action is kept at a minimum so as to minimize the destructive action of the pumping on blood cells. To this end, the invention contemplates the utilization of gravity, either alone or assisted by the gentle steady pressure of a fluid in a plenum chamber communicating with a metering chamber, for evacuating the latter after it has been filled by the pumping action.

In one of its specific aspects, the invention contemplates a pumping arrangement in which a fluid (e. g., air or an inert gas or liquid) above

2

the blood in a metering chamber is alternately subjected to suction and compression so as to alternately draw the blood into and expel the blood from the metering chamber. Such an arrangement has the advantage of avoiding direct contact of the blood cells with moving mechanical parts of a pump.

A further object of the invention is to provide novel liquid level sensitive control means for controlling the operation of an apparatus as specified above. Such control means may take the form of photosensitive means, or electrostatic means, or electric switch means utilizing the blood itself as a portion of the control circuit, and the invention aims to utilize any of these several circuit control mechanisms for controlling the blood interchange apparatus.

In another of its specific aspects, the invention contemplates an arrangement in which the filling and evacuation of a metering chamber is controlled by a pair of controls responsive respectively to minimum and maximum weights of the chamber and contents (determined by emptying and filling of the chamber respectively).

Other objects will become apparent in the ensuing specifications and drawings in which:

Fig. 1 is a schematic view of a modified form of control device of the general type shown in Fig. 8;

Fig. 2 is a detail view of a modified form of circuit controller;

Fig. 3 is a detail view of another modified form of circuit controller;

Fig. 4 is a detail view of another modified form of circuit controller;

Fig. 5 is a schematic view of a blood transfer apparatus embodying one form of the invention;

Fig. 6 is a schematic view of a blood transfer apparatus embodying a modified form of the invention;

Fig. 7 is a schematic view of a modified form of a metering chamber; and

Fig. 8 is a schematic view of a blood transfer apparatus embodying another modified form of the invention.

General features of the invention

In general the invention provides means, such as vessels 10, 10' of Fig. 5 for defining a pair of metering chambers in which blood is metered as it is cross-transferred from the body of a donor, indicated schematically at A to the body of a patient, indicated at B, and from the latter to the donor. The invention also provides a system of flow conduits 13, 13' and 14, 14'; a corresponding set of valves 23, 23' and 24, 24' for controlling

flow therethrough in a manner to effect the result referred to above; and suitable means, such as pumps 60, 60 (Fig. 5) for inducing the flows of blood through the metering chambers.

Valves 23, 24 etc., may be of any known type, suitably selected for use in a system of the type contemplated by the invention. Preferably, the valves are of the general type commonly employed in apparatus (such as hot water bottle apparatus) in which a fluid conducting flexible tube has a short section thereof functioning as a valve under the action of means for pinching the tube so as to collapse it, thereby shutting off flow therethrough. The pinching means comprises any suitable pair of opposed jaw members one of which, in the valve contemplated by the present invention, is actuated by a solenoid.

Metering chambers 10, 10' (as well as all other parts of the apparatus with which the blood makes direct contact) are constructed from inert material, such as, for example, polyethylene or other inert synthetic plastic material, or of glass or metal coated with an inert, non-wettable film (such as a silicone, or other non-wettable coagulation retarding material). A silicone coating is preferred, since it possesses a high degree of coagulation retarding properties (is water-repellent or non-wettable, which retards coagulation because the blood cells have little opportunity to become static by adhering to the non-wetting surface).

Blood withdrawing and injection catheters are indicated at 11, 11', 12 and 12' respectively. Such catheters may be combined in a single instrument as disclosed in my pending application above referred to. Catheters 11 and 12', in the apparatus of Fig. 5, are connected through conduits 14 and 13' and a T-union 15 to the bottom of chamber 10. Catheters 11' and 12 are connected through conduits 14' and 13 and a T-union 15' to the bottom of chamber 10'. Pumps 60, 60 are actuated in opposed phase by means which will be described hereinafter, to cause a flow into one metering chamber while the other is being emptied, and vice versa.

The blood is metered by controlling its flow into and out of the chambers 10, 10' so that such flow will be arrested at upper and lower limits of the blood levels in the respective chambers. Such arresting of flow is brought about through the use of the above mentioned flow control valves actuated by controls responsive to such upper and lower level limits. The liquid level responsive controls may comprise pairs of photoelectric cells 20, 21 and 20', 21' for the respective chambers 10 and 10'. The photocells 21 and 21' may be arranged in communication with transparent portions of the connections between T-unions 15, 15' and the chambers 10, 10'; and the photocells 20, 20' may be arranged in communication with transparent portions of vents 22, extending upwardly from the tops of the respective chambers. Light beams (not shown) may be arranged to shine through the T-unions 15, 15' and vents 22 when not cut off by the columns of blood standing in these connections and vents, and, consequently, the respective photocells will be energized when the liquid columns behind them drop below the light beams to which they are respectively responsive.

The photocells 20, 21, 20', 21' control the operation of respective valves 23, 24', 23', 24 which in turn control flow through the conduits 13, 14', 13', 14 respectively. Where the valves 23, 24', 23', 24 are of the constrictor type, the conduits 75

13, 14', 13', 14 will be of a resilient, readily collapsible tubing of suitable plastic or rubber material, preferably coated internally with an inert, non-wettable film such as that referred to above.

The invention utilizes a suitable system of electrical controls for alternately opening and closing the valves so as to produce the desired flow. For example, valves 23 and 24 may be closed while valves 24' and 23' are open, whereby blood may flow from chamber 10 through conduit 13' into body B while blood from body B flows through conduit 14' into chamber 10'. In the system shown, the flow to and from body A will be cut off during this half-cycle of operation.

As an example of one set of electrical controls that may be utilized, I have shown a plurality of relays 25, 26, 25', 26 responsive respectively to photocells 20, 21, 20', 21' respectively. To this end, the energizing coils of the respective relays may be connected through conductors 27 to the respective photocells and suitably connected to a source of relay energizing electric power which is indicated at E. Each relay 25, 26, etc., has a contact head 41 cooperable with suitable contacts to complete a circuit through a conductor 29 and a solenoid energizing coil 30 to another source of power which is indicated by the reference character F. Coils 30 constitute the energizing coils of valve operating solenoids 31, 32, 31', 32' for operating valves 23, 24, 23', 24' respectively. Each of the solenoids 31, 32, 31', 32' includes a holding coil 33 for maintaining the energization of the respective relay until cut off (e. g., by the opening of a respective limit switch 35 or 35' in the form of the invention shown in Fig. 5). Holding coils 33 may be immediately controlled by conventional solenoid operated holding coil switches 34 each having a movable contact which is operated by the respective solenoid armature, whereby a holding coil will be energized coincidentally with the energization of a respective energizing coil 30.

As each of the solenoids 32, 31' is energized, a holding circuit will be established from power source F through a respective holding coil 33, a conductor (46 for solenoids 31 and 32, 47 for solenoids 31' and 32') to a respective holding coil switch 34.

Each limit switch 35, 35' may include a fixed contact and a swinging arm spring-urged normally into engagement with the fixed contact and adapted to be moved out of engagement therewith by a walking beam 68 forming part of the pump actuating mechanism.

Relays 25 and 25' are of the self-closing type—open when energized, closed when de-energized. Relays 23 and 26 are of the self-opening type—closed when energized and open when de-energized. Solenoids 31, 31', 32, 32' are all of a self-opening type, closing valves 23, 24, 23', 24' when energized, opening the valves when de-energized. For example, the valve-solenoid unit may be spring urged to open position. Photocells 20, 20' become de-energized when the liquid level in chambers 10, 10' rises to maximum height, thereby closing relays 25, 25'. Photocells 21, 21' become energized when the liquid levels in chambers 10, 10' drop to minimum levels, thereby closing relays 26, 26'.

Modified forms of liquid level responsive controls

Fig. 2 illustrates a modified control system embodying electrodes 20a, 21a, of inert metal such as platinum, sealed into the vent 22a and union

15a respectively and adapted to establish respective circuits to relays 25a, 26a when contacted by the upper level of the body of blood in chamber 10a. A ground connection G may also embody an electrode sealed into the bottom of union 15a, below the level of both electrodes 20a and 21a. Circuits are established from ground connection G through the blood to contacts 20a and 21a respectively. This form of circuit controller is not as desirable as the photocell type shown in Fig. 1, for the reason that some electrolysis of blood may take place.

In Fig. 3 I have shown another modification of the control units. In this case, stems 20b and 21b of relays 25b, 26b respectively are actuated mechanically by a float 48 slidably mounted in a guide tube 49 the respective ends of which communicate with union 15b and vent 22b respectively. Tube 49 is perforated to provide communication with chamber 10b. The stems 20b, 21b may, for example, be slidably mounted in bearings in the vent 22b and union 15b respectively, for free sliding movement in response to the camming engagement of inclined end portions of float 48 against the yielding resistance of springs 50 that are operative to return the movable relay members to normal positions when disengaged by float 48.

Fig. 4 illustrates a still further modification of the circuit control units, embodying capacitor elements 20c, 21c embracing vent 22c and union 15c respectively. Capacitor elements 20c, 21c are connected by conductors 21c to conventional electronic relays 25c, 26c adapted, in response to change in the dielectric condition of units 20c, 21c to control the operation of the valve solenoids. Change in dielectric condition of units 20c, 21c will occur when columns of blood enter or leave the passages within vent 22c and union 15c.

Either of the circuit control arrangements shown in Figs. 2, 3 or 4 may be utilized for triggering the operation of solenoids 31, 32, 31' and 32' of Fig. 1, or the corresponding solenoids of the modifications of the general apparatus shown in Fig. 5 et seq.

Suction-compression type apparatus

In Fig. 5 is illustrated a form of the invention in which the metering chambers 10, 10' are supported in fixed positions and in which blood is alternately drawn into the chambers and expelled therefrom by suction-compression units 60. Such suction-compression units may each include a rigid walled housing 61 closed on one side by a flexible diaphragm 62 of material having the characteristics of soft rubber. The diaphragm 62 is sealed to the open mouth of the housing 61 so that no leakage of air past the diaphragm will occur. Each housing 61 communicates with a corresponding chamber 10, 10' through a passage 22. Each diaphragm 62 is attached to a piston 63 carried by a piston rod 64 slidably mounted in a bearing 65. The respective pistons are reciprocated with opposed timing so that when one diaphragm is moving inwardly the other will be moving outwardly and vice versa. This may be accomplished by any suitable means such as for example the walking beam 66, oscillated about a fulcrum pivot 67 by a pitman 68 connected to it by suitable linkage 69, with an electric motor 70 driving the pitman 68 through suitable reduction gearing 71, all shown schematically.

Diaphragms 62 and housings 61 cooperate to define chambers 72 in which the diaphragms will

alternately exert suction and compression against the air therein, which suction and compression stages are transmitted to chambers 10, 10' to draw blood into or expel blood from such chambers.

The system includes transfer conduits 13, 14, 13', 14', controlled by valves 23, 24, 23', 24' which in turn are operated by solenoids 31, 32, 31', 32' under the control of relays 25, 26, 25', 26' respectively as previously described. Solenoid holding circuits are controlled by limit switches 35 and 35', which are operated by the respective extremities of walking beam 66 as indicated.

It is contemplated that the motor 70 may be operated continuously at a speed adjusted to the requirements of the blood transfer operation that is being performed. To provide for some adjustment, the motor 70 may be a variable speed motor. The diaphragms 62 may be of sufficient flexibility to permit of valves 23, 24, 23', 24' being at least occasionally closed somewhat prior to the end of the strokes of pistons 63, so that the fluid flow will be controlled directly in accordance with the valve action rather than in accordance with the complete strokes of the pistons 63. This makes it possible to obtain the desired accuracy of metering action, while allowing the diaphragms to operate continuously at a uniform rhythm. Any substantial movement of a piston 63 either inwardly or outwardly after the closing of a valve has arrested liquid flow into or out of its corresponding chamber 10, 10', may be compensated by a certain degree of collapsing or expanding of the diaphragms 62 radially so as to avoid any substantial increase in the compression or rarefaction of the air within chambers 72.

Operation of suction-compression type apparatus

With the switch 73 closed and the motor 70 operating, reciprocating movement will be transmitted to pistons 63 by linkage 68, 71, 66 and 64, slowly reciprocating the pistons 63 in alternating, opposed rhythm, one piston moving inwardly while the other piston moves outwardly and vice versa. With the parts moving as indicated by the arrows in Fig. 5, atmosphere in the left chamber 10 will be subjected to compression, expelling donor's blood through conduit 13' into patient B, while patient's blood is withdrawn through conduit 14' into right hand chamber 10' by suction applied to this chamber by the upward movement of right hand diaphragm 62. When the rising liquid level has passed photocell 20', relay 25' will be de-energized and thereby closed, establishing a circuit to solenoid 30 of valve 23', interrupting the flow of blood through conduit 14'. When the sinking liquid level in left hand chamber 10 uncovers photocell 21, relay 26' will be energized and thereby closed, establishing a circuit through solenoid 32' closing valve 24' and arresting flow through conduit 13' into patient B. All four valves will then remain closed until the walking beam 66 completes its stroke, whereupon limit switch 35 will be opened, releasing holding coils 33 of solenoids 31 and 32' and allowing valves 23 and 24' to open. Left hand diaphragm 62 will now be moving outwardly and right hand diaphragm inwardly causing donor's blood to be drawn into left hand chamber 10 through conduit 14 and patient's blood to be expelled from right hand chamber 10' through conduit 13 into donor. When the rising liquid level in left hand chamber 10 passes photocell 20, relay 25 will be de-energized, and thereby closed, energizing solenoid 31 and closing valve 23. When falling liquid level

in right hand chamber 10' uncovers photocell 21'. relay 26 will be energized, and thereby closed, energizing solenoid 32 and closing valve 24. This completes a cycle of operation and, with the pistons 63 again moving in the directions indicated by the arrows, the liquid levels in chambers 10, 10' will shortly reach the positions shown in Fig. 5, thus completing one cycle of operation.

Plenum chamber type apparatus

Fig. 6 illustrates a possible modification of the flow inducing arrangement, in which there are interposed between the respective T-unions 15e and chambers 10, 10' pumps 81, 81' each having its outlet connected to a union 15e and its inlet connected to one of the return conduits 14, 14'. Vents 22 communicate with housings 83, closed by distensible diaphragms 84, 84' to define therewith plenum chambers P, P'. The diaphragms 84, 84' are stretched under tension so as to be constrained toward assuming flat positions. The pumps 81, 81' are operative to induce flow into the respective chambers 10, 10' alternately from the respective bodies A and B, under the control of valves 23, 23', 24, 24'. Pumps 81, 81' are driven by electric motors 85, 85' each of which is adapted to be energized coincidentally with opening of a pair of valves 23, 24 (or 24', 23'). For example, motor 85 will be energized upon the simultaneous opening of valves 23 and 24, and the simultaneous opening of these two valves will follow immediately upon the consecutive successive closing of both of valves 23' and 24' as described in detail under the next subheading hereof.

De-energization of a pump motor 85 (or 85') in order to arrest a pumping stage, is effected simultaneously with the closing of a valve 23 (or 23') which in turn occurs when the liquid level in a chamber 10 (or 10') reaches maximum height.

The controls for valves 23, 24, 23', 24' are substantially the same as in the other form of the invention, liquid level responsive controls 20, 20', 21, 21' being connected through conductors 27 to energizing coils of relays 25e, 25e', 26e, and 26e' respectively, and being responsive to liquid level movements so as to close the respective contact heads 28 of relays 25e, etc., against their cooperating contacts in response to the arrival of liquid levels at the maximum and minimum positions respectively. Each such closing of a contact head 28 against its contacts will, through a conductor 29, energize a respective solenoid coil 30 so as to close a respective valve 23, 23', 24 or 24' as the case may be. Each valve, when thus closed, will remain closed by operation of holding coil 33 which becomes energized through a holding circuit including a solenoid operated switch 34.

The solenoid holding circuits are as follows: Contact heads 41 of relays 25e and 26e' are connected in parallel by conductors 46e and 47e' to solenoid operated holding coil control switches 34 of relays 31' and 32' respectively. Similarly, contact heads 41 of relays 25e' and 26e, when they engage their cooperating contacts, will establish holding circuits through conductors 46e' and 47e to solenoid holding coil control switches 34 of solenoids 31 and 32. In each case the two relay contact heads 41 are in parallel so that both contact heads 41 must disengage their cooperating contacts in order to open their respective holding coil circuits.

Motors 85, 85' are energized through relays 86, 86' which are under the dual control of (a) the

valve opening circuits described immediately above and (b) the contact heads 28 of relays 25e, 25e'. Each relay 86, 86' includes a contact head 87 and cooperating contacts adapted, when the relay is de-energized, to establish a circuit through a conductor 88 to a corresponding motor winding 39 (or 39'). Energizing coil 89 of relay 86 (or 86') is connected through conductor 29 to the contacts which cooperate with head 28 of relay 25e (or 25e') whereby, when liquid level of chamber 10 (or 10') reaches the upper limit, and relay 25e (or 25e') is consequently de-energized, closing contact head 28 against its contacts to close valve 23 (or 23'), relay 86 (or 86') will coincidentally be energized to withdraw contact head 87 from its cooperating contacts, thereby breaking the motor circuit of the pump 81 (or 81') thus arresting the rise of liquid in the filled chamber.

Each of the relays 86, 86' includes a holding coil 90 which is energized coincidentally with energizing coil 89 through a holding coil switch 91 the movable contact of which moves in unison with head 87, closing when head 87 opens, establishing a holding circuit through a conductor 92 to conductor 47e (or 47e'). Thus the holding circuit of relay 86 is in parallel with the holding circuits of relays 31 and 32 and the holding circuit of relay 86' is in parallel with the holding circuits of relays 31' and 32'. Consequently, the starting of motor 85 (or 85') will be coincident with the opening of valves 23 and 24 (or 23' and 24').

Operation of plenum chamber type apparatus

Fig. 6 illustrates a stage of operation just preceding the filling of chamber 10' and the emptying of chamber 10. The arrows indicate the flow of patient's blood through conduit 14', pump 81' and union 15e into chamber 10' and the outflow of donor's blood from chamber 10 through union 15e and conduit 13' into patient B. The latter flow is a gravity flow, the chambers 10 and 10' being elevated above the level of the patient and donor sufficiently to provide for gravity evacuation of the chambers.

When the liquid level in chamber 10' reaches the upper limit, photocell 20' will be covered and relay 25e' will be de-energized, resulting in: (a) closing of relay 25e' at head 28, simultaneously energizing relay 31' to close valve 23' and energizing relay 86' to open the same at head 87, de-energizing motor 85', stopping pump 81' and arresting the rise of liquid level in chamber 10'; (b) opening relay 25e' at head 41 so as to open one branch of the holding circuit for relays 31, 32 and 86 (conditioning these relays for operation when the other branch of this holding circuit is opened).

When liquid level in chamber 10 drops to the lower limit (which may occur either before or after the reaching of the upper limit of liquid level in chamber 10') photocell 21 will be uncovered, energizing relay 26e and resulting in (a) closing of relay 26e at head 28 so as to energize solenoid 32' and close valve 24' to arrest the outflow of liquid from chamber 10; and (b) opening relay 26e at head 41 so as to open the other branch of the holding circuits for solenoids 31 and 32 and relay 86 and de-energize these three instruments, resulting in the coincidental opening of valves 23 and 24 and the starting of motor 85 to operate pump 81.

This completes the change-over from one half cycle of operation to another, and the operation

will proceed immediately with a new half cycle in which donor's blood will be pumped through now open valve 23 and conduit 14, pump 81 and union 15e into chamber 10, while patient's blood will be discharged by gravity from chamber 10' through union 15e' and conduit 13 into the donor. Valves 23' and 24' having been closed consecutively, as described above, will remain closed through the operation of holding coils 33, energized by the closing of their control switches 34. Thus the closed positions of these valves will remain unaffected by either (a) the re-energization of relay 25e' occurring shortly after the beginning of the new half cycle, as the result of liquid level in chamber 10' dropping away from its upper level and uncovering photocell 20'; or (b) the de-energization of relay 26e occurring likewise shortly after the beginning of the new half cycle as the result of liquid level again covering photocell 21 as donor's blood is pumped into chamber 10.

In the new half cycle, all valves and relays will remain in the positions last described above until the liquid level in chamber 10 reaches the upper limit (or until the liquid level in chamber 10' reaches the lower limit, whichever occurs first). Assuming that liquid level in chamber 10 reaches the upper limit before chamber 10' is evacuated, photocell 20 will be covered, breaking the circuit to relay 25e, resulting in (a) opening of that relay at head 41, thus opening one branch of holding circuit for solenoids 31' and 32' and relay 86'; (b) closing relay 25e at head 28, thus re-energizing solenoid 31 and returning valve 23 to the closed position shown. When liquid level in chamber 10' reaches its lower limit, photocell 21' will be uncovered, energizing relay 26e' and effecting: (a) opening of relay 26e' at head 41, opening the other branch of holding circuit to solenoids 31' and 32' and relay 86' thus de-energizing the holding coils of these instruments and releasing each of them for movement to their positions in which: (1) valves 23' and 24' return to their open positions shown in the drawing and (2) head 87 of relay 86' re-engages its contacts to re-establish the circuit to motor 85', starting the operation of pump 81'; and (b) closing of relay 26e' at head 28, re-energizing relay 32 and closing valve 24. This completes the second half of a complete cycle of operation, and starts a new cycle of operation in which patient's blood will be pumped into chamber 10' and donor's blood evacuated from chamber 10 and delivered to the patient, all as indicated by the arrows in Fig. 6.

This form of the invention differs from the previously described form in the following particulars: (a) Evacuation of the chambers 10 and 10' is brought about by the pressure of gas in the plenum chambers 85 and 85', responding to the pressure of distended diaphragms 84, 84'. Chambers P, P' may be filled with air or with an inert gas which has a minimum absorption in human blood. (b) Cycling operation is attained without the utilization of mechanically tripped limit switches, the changes of cycle being effected entirely by electrically operated relays responsive solely to the movement of the blood to its respective limits in chambers 10 and 10'.

Apparatus of Fig. 7

Instead of a gaseous atmosphere above the blood in the metering chambers, an inert liquid, such as mineral oil, may be used. In such a case, the arrangement of Fig. 6 could be modified to include a storage chamber 85f above each

metering chamber, communicating with the metering chamber through a passage 22f and in turn communicating with atmosphere through a vent 22g, as shown in Fig. 7. In the arrangements of Figs. 5 and 6, the chambers 10, P, P' respectively could be filled with an inert liquid without otherwise modifying the apparatus. Such an arrangement would have the advantage of avoiding the absorption of gas into the blood being pumped.

The system, modified in accordance with Fig. 7, would further distinguish from the other forms of the invention in that flow from the metering chamber would be a gravity flow. In such modified arrangement inert liquid 19 would float on the body of blood and would rise and fall therewith.

Weight responsive control type apparatus

Fig. 8 illustrates schematically how metering chambers 10h may be controlled by the weight of blood in the chambers. Chambers 10h may be suspended by any suitable counterbalancing arrangement utilizing weights or springs for counterbalancing the chambers in such a manner that when empty, they will exert upward pressure against pressure sensitive control elements such as the strain gages which are indicated schematically at 20h, and when filled, they will exert pressure downwardly against pressure sensitive controls such as the strain gages 21h.

As an example of one arrangement for counterbalancing chambers 10h, Fig. 8 illustrates the mounting of the chambers 10h on levers 99, fulcrumed on fixed supports at 100, and having counterweights 101 adapted to establish an upward load on chambers 10h when the latter are empty, and to be overbalanced when the chambers are filled. The counterbalancing can be so adjusted to the strain gages 20h and 21h that one circuit will be established when the metering chamber is emptied and another circuit will be established when the metering chamber is filled. These circuits may be triggered through relays 25h, 25h', 26h, 26h', which may be the same as relays 25e, 25e', 26e, 26e', of Fig. 6. The remainder of the apparatus and the electrical control circuit, may be the same as that shown in Fig. 6, and consequently has not been illustrated in detail in Fig. 8.

Instead of the strain gages 21h, other pressure or weight sensitive devices such as a weighing device having a pointer equipped with an electric contact, can be utilized. Also, instead of utilizing two of the pressure responsive controls for each chamber, it would be possible to utilize a weighing device equipped with a pointer operating between a pair of contacts, with the pointer playing between the two contacts in accordance with the degree of filling or emptying of the chamber, engaging one contact when the chamber is empty and engaging the other contact when the chamber is full. Such a control in effect would be a combination of the two controls of the previous forms of the invention, the one contact corresponding to one control and the other contact corresponding to the other control. A schematic illustration of such a two-way control device is shown in Fig. 1, the numeral 95 indicating a weighing device having a movable part 99 adapted to be attached to or support the metering chamber 10h, having a base 97 for engagement with a fixed support, and having a pressure responsive pointer 98 playing between contacts 20h and 21h and responsive to pressure

11

against part 93. The pointer 98 may be equipped with corresponding contacts 20h' and 21h', co-operable with contacts 20h and 21h to provide two separate switching units, one adapted to close when the chamber 10h is emptied and the other adapted to close when the chamber 10h is full.

General features

It is to be noted that, in each of the forms of the invention shown, it is impossible for a new cycle or half cycle of operation to commence until the previous half cycle has been completed. The reversal of flow in each chamber occurs exactly at the upper and lower liquid level limits and consequently an accurate metering action is obtained, exactly the same amount of blood being drawn into each chamber in each half cycle operation. Consequently, the amount of blood transferred from the patient to the donor will be exactly the same as the amount of blood transferred from the donor to the patient, and the total quantity of blood transferred will be accurately recorded by recording (either manually or through automatic recording instruments) the number of cycles of operation.

It is possible to use the apparatus not only for blood interchange between a patient and donor, but also for an operation in which blood is withdrawn from a patient while blood or serum coming from a storage chamber (instead of directly from the body of a donor) is injected into the patient. In such an operation, conduits 13 and 14 may be connected, one to a storage vessel from which blood may be drawn into chamber 10, and the other to a receptacle into which the patient's blood may be discharged. After a suitable sterilizing operation, the patient's blood could then be either stored for any future use for which it might be suitable, or it could be returned to the body of the patient in a subsequent cycle of the same general operation in which it is withdrawn. Similarly, the apparatus could be used for withdrawing blood from a donor and injecting it into a storage container for storage and future use, while simultaneously injecting into the donor's veins an inert saline solution to replace the liquid content of the withdrawn blood. In each of such alternative operations it would of course be possible to utilize the metering function of the apparatus to record accurately the quantity of blood taken from a storage vessel and the quantity of blood delivered into a storage receptacle, as well as recording accurately the amount of patient's blood replaced by storage blood or serum; or, in the alternative, the amount of donor's blood replaced by storage blood or a saline solution.

I claim:

1. In a blood transfer apparatus, in combination with a pair of catheter means for insertion into blood channels of respective bodies, each of said catheter means including a withdrawal catheter and an injection catheter; a pair of metering chambers each having restricted passages communicating respectively with its upper and lower extremities, conduits branching from each of the lower passages and communicating with one each of said inlet and withdrawal catheters, means for inducing outflow from one of said chambers and inflow into the other of said chambers and, alternately, inducing inflow into said one chamber and outflow from said other chamber, and means responsive to change in blood level in said upper and lower passages respectively for directing said outflows alternately to one

12

and then the other of said injection catheters and for directing said inflows alternately from one and then from the other of said withdrawal catheters.

5. 2. Apparatus as defined in claim 1, wherein said flow inducing means comprises means for alternately applying suction and compression to the upper regions of the respective chambers.

3. Apparatus as defined in claim 1, wherein said flow inducing means comprises means to pump the blood into the respective chambers, and means yieldingly opposing the inflow into each chamber and operative, when the operation of the pumping means is arrested, to expel the blood

10 15 from the chamber, said yieldingly opposing means comprising means defining a plenum chamber communicating with the upper passage of a respective metering chamber, said last named means including a flexible, elastic diaphragm

20 forming one wall of the plenum chamber and adapted to be distended by the expelling of fluid from the metering chamber into the plenum chamber as the metering chamber is filled with blood, said diaphragm acting to yieldingly impose pressure upon the plenum chamber and thus upon the metering chamber to expel the blood from the metering chamber in the outflow stage of operation of the metering chamber.

4. Apparatus as defined in claim 1, wherein said blood level responsive means comprises photocells communicating with the respective passages so as to be responsive to activating light beams when said passages are empty and to be de-energized when blood columns fill said pas-

35 sages.

5. Apparatus as defined in claim 1, wherein said blood level responsive means comprises capacitors embracing the respective passages and responsive to dielectric condition changes resulting from the movement of blood columns into and out of said passages.

6. Apparatus as defined in claim 1, wherein said blood level responsive means comprises a pair of controls responsive respectively to the weights of respective metering chambers when empty and when full of blood.

7. In a blood transfer apparatus, in combination with a pair of catheter means for insertion into blood channels of respective bodies, each of said catheter means including a withdrawal device and an injection device; a pair of metering chambers; a pair of conduits for establishing communication with the bottom of each metering chamber and with one each of said inlet and withdrawal catheter devices, said conduits functioning for conducting outflow from one of said chambers and inflow into the other of said chambers, and, alternately conducting inflow into said one chamber and outflow from said other chamber, and valve means responsive to change in blood level in said chambers at upper and lower liquid level limits therein, for establishing, in one half cycle of operation of the apparatus, through two of said conduits, consisting in one conduit of each pair, flow paths for flow from one of said withdrawal devices to one of said chambers and from the other chamber to one of said injection devices and, in an alternative half cycle, establishing, through the other two conduits, flow paths for flows from the other withdrawal device to said other chamber and from said one chamber to the other injection device.

8. In a blood transfer apparatus, in combination with a pair of catheter means for insertion

into blood channels of respective bodies, each of said catheter means including a withdrawal device and an injection device; a pair of metering chambers each having restricted passages communicating respectively with its upper and lower extremities; a pair of conduits branching from each of the lower passages and communicating with one each of said inlet and withdrawal catheter devices; means for inducing outflow from one of said chambers and inflow into the other of said chambers and, alternately, inducing inflow into said one chamber and outflow from said other chamber, said last means comprising a pair of pumping chambers communicating with the respective upper passages of said metering chambers, a pair of diaphragms each closing one side of a respective pumping chamber, an electric motor operated means for alternately moving one of said diaphragms inwardly while moving the other diaphragm outwardly and then moving said other diaphragm inwardly while moving said one diaphragm outwardly; and means responsive to change in blood level in said upper and lower passages respectively for directing said outflows alternately to one and then the other of said injection catheters and for directing said inflows alternately from one and then from the other of said withdrawal catheters, said last means including solenoid operated valves having holding circuits, and limit switches actuated by said diaphragm operating means for opening said holding circuits periodically.

9. In a blood transfer apparatus, in combination with catheter means for insertion into blood channels of respective bodies, including a withdrawal device and an injection device; a pair of metering chambers each having restricted passages communicating respectively with its upper and lower extremities; a pair of conduits communicating respectively with said inlet and withdrawal catheter devices; means for inducing outflow from one of said chambers and inflow into the other of said chambers, and, alternately, for inducing inflow into said one chamber and outflow from said other chamber, said last means comprising pumps each having an inlet communicating with a respective withdrawal conduit and an outlet communicating with a respective injection conduit and also with a respective lower passage, a plenum chamber communicating with the upper passage of each of said metering chambers, a distensible diaphragm closing one side of each of said plenum chambers and adapted to be distended when blood is pumped into the respective metering chamber and to exert an evacuating pressure against said blood when the pumping action thereagainst is terminated, and means responsive to change in blood level in said upper and lower passages respectively for directing said outflows alternately from one and then from the other of said withdrawal catheters.

10. In a blood transfer apparatus, in combination with two pairs of catheters for insertion into blood vessels of respective bodies: means defining a pair of metering chambers and a fluid

connection for each chamber for conducting flows alternately into and out of the respective chamber; two pairs of fluid conduits, each pair branching from a respective one of said connections and leading to respective catheters of each pair, the catheters of each body, being connected respectively to one conduit of each pair, and valve means arranged and automatically operable to render two of said conduits, consisting in one conduit of each pair, collectively operative in one half cycle of operation of the apparatus, to conduct flows from one catheter of one body to one of said chambers and from the other chamber to the other catheter of said one body, and to render the other two conduits collectively operative, in an alternate half cycle of operation, to conduct flows to and from the other two catheters, whereby to effect the transfer of a measured quantity of blood from one body to one of said metering chambers and the simultaneous transfer of a measured quantity of the blood of the other body from the other metering chamber to said one body.

11. In a blood transfer device, in combination with two pairs of catheters for insertion into the blood streams of donor and patient bodies respectively, including an injection catheter and a withdrawal catheter for each body: a system of flow conduits including a pair of conduits for each body, connected respectively to the inlet and withdrawal catheters thereof; means defining a pair of metering chambers and a fluid passage for each chamber to function alternately as inlet and outlet therefor, each of said passages being connected to a conduit leading to the injection catheter of one body and to a conduit leading to the withdrawal catheter of the other body; a valve for each conduit, for controlling flow therethrough; means for inducing fluid flows through said passages alternately into and out of the respective chambers, with fluid entering one chamber while fluid is leaving the other chamber, and vice versa; and means responsive to changes in the volumes of fluid in the respective chambers for opening the valves of one of said pairs of conduits and closing the valves of the other pair, in timed relation to the fluid flows in said passages, such that the outflowing fluid from the chamber that is being emptied will flow to the injection catheter of one of the bodies, and the fluid flowing into the chamber that is being filled will come from the withdrawal catheter of the same body.

PETER F. SALISBURY.
